UNITED STATES PATENT OFFICE.

JAMES W. ARROWSMITH, OF MORRISTOWN, NEW JERSEY.

SHOE-SOLE SUPPORT.

No. 873,001.

Specification of Letters Patent.

Patented Dec. 10, 1907.

Application filed December 12, 1906. Serial No. 347,502.

To all whom it may concern:

Be it known that I, JAMES W. ARROWSMITH, a citizen of the United States, and a resident of Morristown, in the county of Morris and State of New Jersey, have invented certain new and useful Improvements in Shoe-Sole Supports, of which the following is a specification.

The invention relates to supports for the soles of boots, shoes and the like and particularly to supports adapted to strengthen and preserve the proper form of that portion of the sole of the shoe which connects the heel and the sole proper and is commonly called the shank. Its objects are, among others, to provide a light, strong and durable support of simple and inexpensive construction, which will have the required strength and at the same time will not add materially to the weight of the shoe or cause discomfort to the wearer.

It also has for its object the provision of a support which will permit of adjustment within certain limits to adapt it to the size and shape of the shoe and which may be quickly and securely placed in position without necessitating special construction of the shoe or any part thereof.

The invention is illustrated in the accompanying drawings in which

Figure 1 is a plan view of a brace or support embodying the improvements, with the sole of the shoe shown in dotted lines; Fig. 2 is a vertical longitudinal section taken on the line 2—2 of Fig. 1; Fig. 3 is a vertical cross-section on the line 3—3 of Fig. 1; Fig. 4 is an underside view of the support.

The invention can be best explained by describing the preferred process of manufacturing the support shown in the drawings, which is as follows: A piece of metal is first taken, and a blank stamped out of it, substantially of the outline and size shown in Figs. 1 and 4. This blank is then placed in suitable dies and the slits B and holes C made therein. The perforated blank is then placed in other dies which hold the tongue D and bend it laterally, and at the same time stretch the side portions E and press them away from the tongue D so that they are disposed in a different plane and curved longitudinally, whereas the said tongue is not so curved. In this or an earlier operation the blank is arched from end to end. This leaves the central transversely curved tongue

D comparatively straight and in approximately the same plane with the under portions F, while the side portions E are arched from end to end, the highest point of the arch being at about the middle of the support. In this operation the horizontally turned end portions G are formed. These end portions are adapted to rest upon the lower sole and heel of the shoe, and the support is secured in place by means of nails or screws passing through the holes C.

It will be understood that the support A, is curved on a comparatively large radius from end to end in order that it shall conform to the shape of the shoe at the part where it is applied and that the tongue D, while forming substantially the chord for the arc described by the support, may also be slightly curved. It will also appear that the peculiar form and construction of the support give it unusual strength and durability. This construction also permits the support to be used in either right or left shoe and therefore makes it unnecessary to manufacture or sell the same in pairs.

The dies used in the stamping operation are so formed that the tongue D is transversely curved on a comparatively short radius, the said curvature gradually diminishing toward the ends of the tongue and merging in the end portions F. This construction, in addition to increasing the normal strength of the arch formed by the main part of the support will check the depressing of the same under extraordinary weight by coming in contact with the portion of the shoe beneath it.

While the support is specially adapted to be incorporated in the sole of the shoe and to form a permanent part of the same, it may be placed in the shoe after the same is finished and rest upon the top of the insole, and in this position will provide a very effective support for the instep of the foot, and will also prevent the same from flattening and destroying the shape of the sole as well as causing lameness.

What I claim is:

1. In a device of the character described, the combination of a metallic plate provided with longitudinal slits and a tongue of metal between said slits and secured to the plate near its ends, but out of contact therewith intermediate the ends.
2. In a device of the character described,

the combination of a plate of sheet metal of greater length than width, curved in one plane and arched from end to end in another plane and provided with longitudinal curved slits intermediate its ends, a tongue of metal connected to the said plate near the ends thereof and extending across its arch in a substantially straight line, said tongue being curved from side to side, and normally out of contact with the plate at its medial parts.

3. In a device of the character described, the combination of a plate of sheet metal of greater length than width, arched from end to end and provided with longitudinal curved slits intermediate its ends, a tongue of metal connected to the said plate near the ends thereof and extending across its arch in a substantially straight line, said tongue being curved from side to side, and normally out of contact with the plate at its medial parts.

4. In a device of the character described, the combination of a plate of sheet metal of greater length than width, arched from end to end and provided with longitudinal slits intermediate its ends, a tongue of metal connected to the said plate near the ends thereof and extending across its arch and having one of its surfaces in a substantially straight line, said tongue being curved from side to side.

5. A device of the character described consisting of a piece of sheet metal of greater length than width having substantially plane surfaces at its ends and a curved medial portion integral therewith and portions between said medial curved portion and the edges of the plate disposed in a different plane thereto.

6. In a device of the character described, the combination of a plate of sheet metal of greater length than width, curved and arched from end to end and provided with longitudinal slits intermediate its ends, a tongue of metal connected to the said plate near the ends thereof and extending across its arch in a substantially straight line, said tongue being curved from side to side, and normally out of contact with the plate at its medial parts.

7. In a device of the character described, the combination of a plate of sheet metal of greater length than width, curved and arched from end to end and provided with longitudinal slits intermediate its ends, a tongue of metal connected to the said plate near the ends thereof and extending across its arch in a substantially straight line, and normally

out of contact with the plate at its medial parts.

8. In a device of the character described, the combination of a plate of sheet metal of greater length than width, arched from end to end and provided with an integral tongue of metal connected to the said plate near the ends thereof and extending across its arch in a substantially straight line, said tongue being curved from side to side and said plate being provided with an opening above the tongue.

9. An instep support comprising a metal plate arched and curved from end to end, and having a concavo-convex medial portion, the curve of the edge of the plate being of greater radius than the curve of the other edge, so that by reversing the plate it may be made to bear the same relation to either foot and a portion of the plate substantially straight in cross-section between said concavo-convex portion and each edge.

10. In an instep support the combination of a plate of sheet metal arched from end to end to approximate the arch of the instep, a portion of said plate extending substantially from end to end flat in transverse cross-section, and another portion extending from end to end curved in transverse cross-section, and below the plane of the said flat portion and said plate being provided with an opening above the tongue.

11. The combination of a metal plate arched from end to end, a brace or truss portion approximately straight from end to end, secured to the said plate at its ends and extending longitudinally thereof said portion being curved from side to side and normally out of contact with the plate intermediate its ends and said plate being provided with an opening above the tongue.

12. A device of the character described, comprising a piece of sheet metal arched longitudinally and having curved side edges, a depressed medial portion extending longitudinally of the plate and being located within said side edges, the said depressed portion being curved to correspond to said edges.

Witness my hand this 3rd day of December 1906, at the city of New York, in the county and State of New York.

JAMES W. ARROWSMITH.
